UNITED STATES PATENT OFFICE.

WARREN H. TAYLOR, OF STAMFORD, CONNECTICUT, ASSIGNOR TO THE
YALE & TOWNE MANUFACTURING COMPANY, OF SAME PLACE.

DESIGN FOR A LOCK-CASE.

SPECIFICATION forming part of Design No. 26,709, dated March 2, 1897.

Application filed January 21, 1897. Serial No. 620,151. Term of patent 14 years.

To all whom it may concern:

Be it known that I, WARREN H. TAYLOR, a citizen of the United States, and a resident of Stamford, in the county of Fairfield and State 5 of Connecticut, have invented and produced a new and original Design for a Lock-Case, of which the following is a specification, reference being had to the accompanying drawings, forming a part thereof.

10 Figure 1 is a perspective view showing my design looking at one side of a lock-case. Fig. 2 is a perspective view showing my design looking at the other side of the lock-case.

15 The leading feature of my design consists in the raised and sunken panels connected by ribs.

Located on the sides of the lock-case are depressions providing sunken panels and raised surfaces providing elevated panels. Surrounding and connecting these panels is a 20 beading providing ribs.

Having thus described my invention, the following is what I claim as new therein and desire to secure by Design Letters Patent:

The design for a lock-case substantially as 25 herein shown and described.

WARREN H. TAYLOR.
